UNITED STATES PATENT OFFICE.

EDWARD POSSON, OF CHICAGO, ILLINOIS.

GRAIN-DOOR FOR CARS.

1,352,692.

Specification of Letters Patent.

Patented Sept. 14, 1920.

Application filed June 5, 1916. Serial No. 101,798.

To all whom it may concern:

Be it known that I, EDWARD POSSON, a citizen of the United States, residing at Chicago, in the county of Cook and State of Illinois, have invented certain new and useful Improvements in Grain-Doors for Cars, of which the following is a specification.

This invention relates to doors for freight cars, and the like, and the principal object 10 of the invention is to provide an improved grain door. A further object is to provide an improved sectional grain door having improved means for supporting the sections thereof in operative and inoperative positions. Still another object is to provide a 15 grain door having a plurality of sections which are slidable in vertical guideways, in combination with improved means for supporting said sections adjacent the door opening in positions parallel to the positions which they normally occupy when closing the door opening. A further object is to provide an improved door section, in combination with improved brackets for supporting the door sections when they are displaced 20 from normal position closing the door opening. Another feature is the provision of improved brackets for supporting the door sections and improved means for mounting said brackets adjacent the door opening. Other objects relate to features of construction and arrangement, as will appear more 25 fully hereinafter.

These and other objects of the invention 30 will appear more clearly from the following specification, taken in connection with the accompanying drawings, in which one embodiment of the invention is illustrated.

In the drawings—

Figure 1 is a longitudinal sectional view 35 through a freight car, showing a side elevation of my improved sectional grain door viewed from the interior of the car.

Fig. 2 is a perspective view, showing my 40 improved door holder supporting the door sections in inoperative position.

Fig. 3 is a transverse vertical section, taken along the line 3—3 of Fig. 1.

Fig. 4 is a detail sectional view, taken on 45 the line 4—4 of Fig. 3.

Fig. 5 is a perspective view, showing my 50 improved bracket or door section holder viewed from the side thereof opposite to that shown in Fig. 2.

Fig. 6 is an enlarged vertical section, taken 55 through the upper part of the car and the

door sections when the latter are supported by the brackets; and

Fig. 7 is a horizontal sectional view, taken 60 on the line 6—6 of Fig. 5.

In the accompanying drawings the side walls 10 of the freight car are shown as comprising the inside sheathing 10^a and the outside sheathing 10^b. Door openings 11 are formed in the opposite car walls, door 65 posts 12 extending vertically at each edge of the door opening, with frame members 13 extending between the posts at the upper edges of the openings. Metal plates 14 are mounted on the floor 15 of the car, between 70 the door posts, forming door sills. The usual purlins 16 extend longitudinally of the car and over the members of the door frames, having attached thereto by suitable means the purlin plates 17. Z-bars 18, at 75 attached to the outer purlin plates, may serve as guides or tracks for the usual outside doors. The purlins and purlin plates serve to support the outer edges of the roof 20, and the intermediate parts of the roof are 80 supported by transversely extending carlines 21, which are secured at their ends to the purlins at the sides of the car. The usual running board 22 is mounted above the roof.

Each door post 12 has secured to the 85 inner corner or edge thereof a vertically extending sheet metal reinforcing plate 24 of angle form, which may be secured to the door post by nails 25, or other suitable means. A door jamb 26 is secured to the 90 inner side of the car wall and to the adjacent door post at each edge of the door opening. A sheet metal angle plate 27 serves to reinforce the edge of this jamb which is directed toward the door opening, 95 and also a part of the undercut notch 28 which is formed in the jamb. A sheet metal guide plate 29 is attached to each of the door jambs 26 by means of screws 30, or the like, and these guide plates seat in the 100 notches 28 and extend beyond the edges 26^a of the door jambs to form guideways 31 for the edges of the sectional grain door.

The grain door consists of a plurality of door sections in the form of plates or 105 sheaves, which are preferably formed of wooden boards 35^a, with metal sheathing 35^b extending entirely around them and secured thereto by rivets 36, or the like. Each longitudinal edge of each door section is provided with a notch 37, which 110 notches are oppositely disposed at the op-

posite edges of each door section, so that when the door sections are placed in position to close the door openings, as shown in Fig. 1, these notches and the corresponding 5 projections 37^a will interlock with each other to form a grain-tight closure. It will be understood that the vertically extending ends of the door sections are adapted to engage the guideways in which they are vertically movable, so that a grain-tight closure is formed along the vertical edges of the 10 door, as well as between each pair of door sections. When the sections are in door-closing position, as shown in Figs. 1 and 3, 15 the longitudinally extending projection 37^a on the lowermost section is adapted to overlap the inner edge of the door sill or plate 14 adjacent thereto, so that a grain-tight closure is also formed along the lower edge 20 of the door opening. It will be seen that the reinforcing plates 24 and 27 serve, with the plates 29, to form durable guideways which will not become materially worn after continued use.

25 One or more of the door sections 35 is provided at each end with apertures which are adapted to align with corresponding apertures 29^a and 12^a, formed in the guide plates 29 and door post, respectively, so that 30 pins 40 may be passed through these aligning apertures to secure the door sections in fixed position closing the corresponding door opening. These pins may be attached to chains 41, which are connected to suitable staples 42 engaging the car wall.

Each of the door sections is provided with a pair of hand holes or depressions 43 on the outside thereof, and a corresponding pair 43^a on the inside thereof, these depressions being diagonally disposed on opposite sides of the door, and having the metal sheathing 35^b pressed into them. These hand holes may be engaged by the fingers of the operator to move the corresponding 40 door section vertically in the guideways in order to open the grain doors. This opening is effected by moving the sections successively in the guideways until they have passed to such positions at the upper end of 45 the guideways that they may be displaced horizontally to be supported in the door section holders or brackets 45.

Each of the brackets is preferably formed of sheet metal, and comprises a main wall 55 or end plate 45^a adapted to engage the ends of the door sections, a vertically-extending longitudinally-directed flange 45^b adapted to engage the vertical edge of the innermost door section when the door sections are supported therein, a horizontal flange 45^c adapted to engage and support the lowermost edges of the door sections, and a flange 60 45^d directed toward the end of the car and which is adapted to be secured to the adjacent purlin and door post, between said

members and the door jamb, which is partially cut away to receive the flange. Each of the flanges 45^d is provided with a plurality of apertures adapted to be engaged by screws 46, by means of which the bracket 70 is attached to the purlin and door post. The upper parts of the guide plates 29 are bent horizontally, as shown at 29^b, and riveted, or otherwise secured, to the horizontally-extending flanges 45^c of the brackets. 75 The extremities of the parts 29^b are directed vertically around the corners of the brackets, and riveted, or otherwise secured, to the vertical flanges 45^b of the brackets. The portion of each flange 45^c adjacent the door 80 opening is bent upwardly to form a lug or flange 45^e adapted to engage the edge of the last door section to be placed in the bracket, in order to prevent displacement of the door sections from the brackets into the guideways. Each bracket also comprises a transversely-extending guiding and retaining flange 45^f, formed on the upper part thereof and directed toward the opposite side of the door opening. These last-named flanges 85 are inclined inwardly and downwardly, as shown particularly in Figs. 3 and 5, the space between the inner extremities of these flanges and the horizontally-extending flanges 45^c being substantially equal to the 90 vertical dimensions of the door sections. The outer extremities of the flanges 45^f are spaced above the upper extremities of the flanges 45^e a distance which is also slightly greater than the vertical dimensions of the 95 door sections, so that when the sections are passed upwardly in the guideways they may be displaced horizontally from the upper ends of the guideways between the flanges 45^e and the inner extremities of the 100 flanges 45^f, and then moved horizontally into the brackets, by which they are supported in inoperative positions. All of the flanges are preferably formed integrally with the body portion 45^a of the bracket. 105

The upper extremities of the vertically-extending flanges 45^b are secured to the longitudinally-extending purlins or frame members 48, which underlie the roof of the car and are attached to the transversely-extending carlines 21. It will be seen that 110 these carlines are secured against relative displacement by means of the tie rods 49. In this manner the brackets 45 are rigidly supported in position adjacent the car roof near 115 the upper edges of the door openings, and it will be seen that the outermost parts of the brackets form continuations of or communicate with the guideways 31, so that the door sections may be passed directly into 120 the brackets, by which they are supported when not in use. A sufficient number of door sections may be provided to close the door opening, or to close the opening with the exception of a small space adjacent the 125 130

upper edge thereof, and the brackets are preferably formed of sufficient size to engage the door sections somewhat closely when all of said sections are in position in 5 the brackets.

It will be seen that the plates 24 and 29 engage somewhat closely the edges of the door sections and the end walls 26^a of the guideways engage closely the ends of the 10 sections, so that said door sections cannot be removed bodily from the guides except into the brackets which are adapted to receive them after they have been moved vertically. The end plates 45^a of the brackets 15 at opposite sides of each door are spaced apart a distance sufficient only to permit free movement of the door sections into the brackets and the horizontal and vertical flanges 45^c and 45^b, respectively, extend only 20 slightly beyond the door posts and guide plates, as shown in Fig. 1, in order not to obstruct the door opening. In combination with the foregoing features of construction, the inclined upper flanges 45^c have been provided in order to prevent removal of the 25 door sections from the brackets, which removal might otherwise be accomplished, when the brackets of a door contain only a single door section, if said section were tilted about horizontal and vertical axes until 30 its ends clear the lower flanges 45^c, or one of the vertical flanges 45^b. But the inclined flanges 45^c prevent tilting in a vertical plane of the end of the door section which is disposed adjacent one of the flanges 45^b and the inclination of the door section longitudinally of the car wall within the confines of the brackets adapted to contain the door sections of a single door will not cause the 35 ends of the door section to clear the edges of the lower horizontal flanges 45^c, or one of the flanges 45^b. Thus it will be seen that after the door guides, brackets, and door sections have been assembled on the car, it 40 is impossible to remove any of the door sections from the guides or brackets, and the theft or unauthorized removal of the sections is prevented.

It will be apparent that this novel and 50 convenient location of the brackets in combination with the advantageous features of construction thereof make it possible to support the door sections in inoperative positions in the smallest space possible. It is 55 an important advantage that the door sections occupy relatively small spaces when stored in or supported by the brackets, and an important feature of the invention is the construction and arrangement of the parts 60 whereby the door sections are supported in the brackets in positions substantially parallel to the planes of the door openings, or to the planes of the guideways, so that in passing the sections from the guideways to 65 the brackets, or vice-versa, it is unnecessary

to tilt or change the inclination of the door sections, thus making it possible to manipulate the sections much more readily and conveniently. During the operation of filling the car with grain the door sections may 70 be lowered successively to increase gradually the amount of closure of the door opening or openings. It will be seen that this operation may be readily effected from the outside of the car which is an important feature of the invention. 75

While the invention has been described in connection with a particular embodiment thereof, it will be understood that it may be constructed in various forms without departing from the scope thereof as defined in the appended claims. 80

I claim:

1. In a device of the class described, a car wall having a door opening therein, a door comprising a plurality of heavy metallic complementary sections, vertically extending guideways for said sections, brackets detachably secured to the inside of said wall at opposite sides of and adjacent the upper part of said door opening, said brackets being arranged to communicate with said guideways and having horizontal flanges to coact with the lower edges of said sections to support the same in inoperative positions 95 parallel to the plane of said door when it is closing said opening, and lugs projecting upwardly at the inner edges of said brackets to prevent accidental displacement of said sections from said brackets, said brackets being located close to said wall and to the roof of said car with the lower walls of said brackets lying below the plane of the upper edge of said door-way whereby the lower edges of said door sections when supported in said brackets may be engaged successively at their middle points by an operator located at the outside of said car in order to lift said sections successively over 100 said upwardly projecting lugs and permit them to fall by gravity into said guideways 105 to close the door opening. 110

2. In a device of the class described, a car wall having a door opening therein, a door comprising a plurality of complementary sections, guideways extending vertically along the edges of said door opening, and holders communicating with said guideways and arranged to receive said sections, said holders comprising horizontally-extending parts adapted to support the end portions of said sections, end plates arranged to engage closely the ends of said sections, upwardly-extending lugs over which said sections may be passed from said brackets to 125 said guideways, upwardly-extending parts spaced from said upwardly-extending lugs sufficiently to receive said sections therebetween when the latter are parallel to each other, and upper inclined parts adapted to 130

permit displacement of sections over said lugs and to prevent displacement of the innermost section upwardly from said horizontal parts.

5. In a device of the class described, a door post, a door jamb attached to said post, a guide plate detachably connected to said door jamb to form a guideway between said plate and post, a grain door comprising a plurality of sections movable in said guideway, and a bracket adapted to receive said sections therefrom and to support the same in inoperative position.

15. In a device of the class described, a door post, a door jamb attached to said post, a guide plate detachably connected to said door jamb to form a guideway between said plate and said post, a grain door comprising a plurality of sections movable in said 20 guideway, and a bracket adapted to receive said sections therefrom and to support the same in inoperative positions, said bracket comprising a flange secured to said door post and interposed between said door post 25 and jamb.

30. In a device of the class described, a car wall having a door opening therein, a door comprising a plurality of vertically movable sections, guideways for said sections along the vertical edges of said opening, and brackets secured to the insides of said wall at opposite sides of and adjacent the upper part of said door opening, said brackets having upwardly projecting lugs 35 over which said door sections must be lifted in passing them to and from said guideways, said brackets comprising parts for supporting said door sections parallel to each other in vertical planes with the lower edges thereof extending below the upper edge of the door opening, so that the lower edges of the door sections can be engaged by an operating member held in the hand of the operator.

40. In combination, a car wall having a door opening therein, guideways along the vertical edges of said door opening, a grain door comprising a plurality of horizontally extending complementary sections engaging 45 said guideways, brackets secured to said wall adjacent the upper corners of said door opening and communicating with said guideways, said brackets each comprising an

end wall with a transverse vertical wall and a smooth lower wall extending from the end 55 wall toward the other bracket, and lugs extending upwardly from the ends of said lower walls parallel to said vertical walls and adjacent said guideway, said door sections being adapted to be lifted over said 60 lugs and to be supported parallel to each other in vertical planes with their edges resting on said lower horizontal walls, the group of door sections being adapted to fit snugly between said lugs and said vertical 65 walls, said sections being adapted to be passed to a position adjacent said lugs by sliding the lower edges thereof on said smooth walls.

7. In combination, a car wall having a 70 door opening therein, guideways along the vertical edges of said door opening, a grain door comprising a plurality of horizontally extending complementary sections engaging 75 said guideways, brackets secured to said wall adjacent the upper corners of said door opening and communicating with said guideways, said brackets each comprising an end wall with a transverse vertical wall and a horizontal lower wall extending from 80 the end wall toward the other bracket, and lugs extending upwardly from the ends of said lower walls parallel to said vertical walls and adjacent said guideway, said door sections being adapted to be lifted over said 85 lugs and to be supported parallel to each other in vertical planes with their edges resting on said lower horizontal walls, the group of door sections being adapted to fit snugly between said lugs and said vertical 90 walls, said sections being adapted to be passed to a position adjacent said lugs by sliding the lower edges thereof on said horizontal walls, said end walls being spaced apart a distance slightly greater than the 95 length of the door sections, the distances between said vertical walls and said lugs being proportioned to prevent the removal of the door sections from said brackets by tilting them transversely of the car, when 100 only one of said sections is supported by said brackets.

In testimony whereof, I have subscribed my name.

EDWARD POSSON.
